UNITED STATES PATENT OFFICE.

EDWARD J. BRANDT, OF WATERTOWN, WISCONSIN, ASSIGNOR TO
BRANDT CASHIER COMPANY, OF CHICAGO, ILLINOIS, A CORPO-
RATION OF ILLINOIS.

KEY-HOLDER.

No. 825,184.

Specification of Letters Patent.

Patented July 3, 1906.

Application filed April 8, 1904. Serial No. 202,205.

To all whom it may concern:

Be it known that I, EDWARD J. BRANDT, a citizen of the United States, residing at Watertown, in the county of Jefferson and State 5 of Wisconsin, have invented certain new and useful Improvements in Key-Holders, of which the following is a specification.

My invention relates to key-holders, and comprises a novel form and construction of 10 key-holder wherein one of the parts or elements is adapted to serve as an identification-tag.

The object of the invention is to provide a simple, secure, and easily-manipulated key- 15 holder which may also combine therewith means for identifying the owner of the keys.

To this end the invention consists in a key- 20 holder chiefly characterized by the combination of a notched plate and a spring-tongue secured thereto and covering the notch, said plate in the preferred embodiment of the invention also constituting an identification-tag.

I have illustrated my invention in two 25 forms, in which it may be embodied in the accompanying drawings, wherein—

Figure 1 is a plan view of the preferred form of the invention. Fig. 2 is an end view of the combined lock and identification-tag. 30 Fig. 3 is a view similar to Fig. 1 of a modification wherein the lock itself in slightly-modified form also constitutes the holder for the keys, and Fig. 4 is a cross-sectional view on the line 4-4 of Fig. 3 viewed in the direction 35 of the arrow.

Referring to the drawings, and first briefly describing the preferred form of the invention, (illustrated in Figs. 1 and 2,) 5 designates a tag preferably cut or stamped from solid sheet 40 metal and of the substantially oval form shown. One end of this tag is cut out or notched, as shown at 6, and the said notched end of the tag is countersunk on one face thereof on either end of the notch, as shown at 7, Fig. 45 2, the countersink extending around and along substantially one-half of one side of the tag, as indicated at 8. In the countersink is fitted a spring-tongue 9, shaped and bent to just fill the countersink and conform to the 50 outline form of the tag and lying flush with the surface of the latter. The inner end of the tongue is securely riveted to the tag, as shown at 10, and its free end overlies and

closes the notch 6. 11 designates an ordinary chain upon which the keys 12 may be strung, the two ends of said chain being provided with rings 13, which may be slipped over the free bent end of the tongue 9 by simply springing the latter upwardly sufficiently to slip the rings under and over the free end of the tongue. As soon as the rings have passed down over the tongue, so as to lie within the notch 6, the free end of the tongue under the elasticity of the latter snaps back into the countersink, thus locking 65 the two ends of the chain together. Either face of the tag presents a plain surface on which may be engraved or otherwise applied a name or registration number or other means of identification, as indicated. 70

The device above described is simple, economical to make, and very easy of manipulation, a slight upward or outward springing of the tongue by the thumb or finger of the operator sufficing for the application of the 75 chain 11 thereto, and a slight outward pull of the chain sufficing to draw either or both of the rings 13 off the end of the tongue, the latter yielding sufficiently to permit withdrawal.

The lock having the spring-tongue hereinabove described may be so formed as to serve also as a direct ring or holder for the keys, dispensing with the chain 11, especially where the bunch of keys is a small one. Such a modification is illustrated in Figs. 3 and 4, 85 85 wherein 5^a constitutes the tag, having a cut-out notch 6^a, generally similar to the notch 6 of Fig. 1, but larger. The tongue 9^a is secured in a marginal countersink 8^a, lying on either side of the notch in the manner already described in connection with Fig. 1, and operates to removably secure the keys 12^a by their apertured or annular heads in the same manner that the rings 13 of the chain 11 are removably secured in Fig. 1, the enlarged 95 notch 6^a providing space for the reception of one or more keys. This modified form of the invention, which dispenses with an intermediate key confining and retaining member, such as the chain 11, may, as above stated, 100 be conveniently employed where the keys are small or comparatively limited in number; but for general purposes I prefer to employ the chain 11 or an equivalent member, which may readily be made of any length suitable 105 to the number of keys comprised in any par-

ticular bunch. In both forms the plain flat member 5 serves the useful double function of a mechanical element of the lock or holder and also of an identification-tag. Of course 5 the particular form of the tag-plate and of its spring-tongue is immaterial, as is also the particular location of the notch and the tongue relatively to the tag-plate; but I prefer the form and relative arrangement shown 10 and described.

I claim—

- 15 1. In a key-holder, the combination with a plate having a minor portion of its periphery cut away, of a spring-tongue fast with said plate at one end and overlying said cut-away portion of the plate to form an inclosed space, the free end of said tongue overlapping the plate at one end of said cut-away portion, substantially as described.
- 20 2. In a key-holder, the combination with a plate having a minor portion of its periphery cut away, of a spring-tongue fast with said plate at one end and overlying said cut-away portion of the plate to form an inclosed space, 25 said tongue overlapping but disconnected

from said plate for some distance inwardly from both ends of said cut-away portion of its periphery, substantially as described.

3. In a key-holder, the combination with a 30 flat plate having a notch formed in its periphery and countersunk marginally on both sides of said notch, of a spring-tongue fitted to the countersunk margin of said plate and secured to the latter at one end and having its free end overlying and closing said notch, 35 substantially as described.

4. In a key-holder, the combination with a flat oval plate having a peripheral notch formed in one end thereof and countersunk marginally across the end of said notch and 40 down one side of the plate, of a spring-tongue fitted to the countersunk margin of said plate and lying flush with the surface of the latter, said tongue being secured to the plate at one end and having its free end overlying and 45 closing said notch, substantially as described.

EDWARD J. BRANDT.
